UNITED STATES PATENT OFFICE.

GEORGE C. BAUMAN, OF CHICAGO, ILLINOIS.

PAPER TRIMMING AND PASTING MACHINE.

No. 929,274.

Specification of Letters Patent.

Patented July 27, 1909.

Application filed September 10, 1908. Serial No. 452,415.

To all whom it may concern:

Be it known that I, GEORGE C. BAUMAN, a citizen of the United States, and a resident of the city of Chicago, in the county of Cook and State of Illinois, have invented certain new and useful Improvements in Paper Trimming and Pasting Machines; and I do hereby declare that the following is a full, clear, and exact description of the same, reference being had to the accompanying drawings, and to the letters of reference marked thereon, which form a part of this specification.

This invention relates to a paper trimming and pasting machine and more particularly to a paper trimming and pasting machine adapted for use in trimming and pasting wall paper or the like preparatory to its application to the wall.

20 The object of the invention is to provide an exceedingly simple, cheap and durable device for the purpose specified containing a receptacle for the paste and means for spreading the paste upon the back side of the 25 paper while drawing the paper through the machine and trimming the same.

It is also an object of the invention to provide a machine of the class described in which brushes are not used, and in which 30 nevertheless the amount of paste delivered to the paper is limited to the proper amount required for satisfactory application.

It is a further object of the invention to 35 provide a cross cutting device to enable the paper to be cut exactly to lengths after it is trimmed and pasted.

The invention consists in the matters hereinafter described and more fully pointed out and defined in the appended claims.

40 In the drawings: Figure 1 is a side elevation of a device embodying my invention. Fig. 2 is a central longitudinal section thereof. Fig. 3 is a fragmentary front elevation thereof.

45 As shown in said drawings: A indicates a tank or receptacle which may be constructed of cast or of sheet metal, or of any suitable material, and which is designed to contain the paste in suitable consistency and which 50 also serves as the frame or foundation of the machine. The side walls of said tank, as shown, are provided at each end with upwardly directed arms or brackets $a-a'$, in which are provided transverse slots or 55 notches and at the top, in which is journaled at the front end a roller a^2 , conveniently con-

structed of a section of suitable length of soft steel shafting. At the rear end of the machine in the bracket a' , a shaft a^3 , is journaled. This, as shown, is of small size to 60 permit the same to be inserted through the center of a roll of wall paper or the like, and as shown, said shaft is provided at opposite ends with collars a^4 , which hold the paper in operative position on the roll and assist in 65 guiding the same to the knives. On the outer end of the shaft a^3 , where the same protrudes beyond the yoke ends of the brackets a' , is threaded or otherwise secured a button or head a^5 , which serves to hold the shaft 70 from end movement. Between the middle of said receptacle and said rear shaft or roll is an upwardly extending yoke bracket arm B, adapted to receive the journals for two rollers $b-b'$, and which, as shown, rest 75 one upon the other and between which the paper X, extends. Said rolls may, if desired, be also constructed of a suitable section of shafting to afford weight and sufficient tension for the paper or may be constructed of wood or any suitable material. Within the receptacle and adjustably secured on said shafts in any suitable manner, are coating, peripheral disk knives b^3-b^4 , 80 which serve to trim the paper as it is drawn 85 therebetween. One of said knives b^4 , is secured to a collar which is provided with a set screw and is thereby adjustable on its shaft and the other knife b^3 , engages the outer side of the disk knife b^4 , and is pressed 90 thereagainst to make a shearing cut at all times of the spring b^5 , secured on the shaft between the collar and bracket arm B. Between the front roll a^2 , and the trimming rolls is journaled a pasting roll D. This is 95 conveniently constructed of wood and journaled in any suitable manner and the yoke bracket d, on each side of the frame prevents end movement of the pasting roll, said roll being of sufficient size to permit the periphery thereof to extend to near the bottom of 100 the receptacle.

Should the roll be of wood or any absorbent material more paste than required might adhere thereto and be carried upwardly by 105 the paper X. For the purpose of preventing this, a scraping blade D', is secured on the frame transversely thereof with its edge bearing against the periphery of the roll, and is held in place by cap screws extending through the transverse slots in said rod or bar, and permit the same to be adjusted 110

from or toward the pasting roll to scrape excess material therefrom.

Means are provided also for cutting the paper transversely when the desired length has been pasted. For this purpose, as shown, curved arms E, are pivotally engaged on the front end of the machine, one on each side thereof and are connected at the top by means of a shaft e, extending transversely 10 of the machine and also by means of a straight edge or blade e', rigidly secured between said arms and the inner edge of which is adapted to bear against the front roll a², while the paper is being cut transversely. 15 Pivotally engaged to depend from the bar e, is a sliding cutting head e². This, as shown, consists of a block or bar slidably engaged on said rod and provided at its lower end is a stud e³, on which is journaled a cutting 20 disk e⁴, and as shown, a handle e⁵, is provided on said block or bar e², to permit the knife to be moved transversely the paper for the entire width of the machine. As shown, 25 strong pulling springs e⁶, are connected at the outer ends of said yoke arms E, and to the frame, as shown in Figs. 1 and 2, in a manner such that when the arms are swung outwardly with the spring under tension, the draft of the spring will fall outside of 30 the pivot e⁷, for said arms, but when said arms are thrown upwardly to bring the straight edge e', against the paper on the roll a², to position the cutter for severing the sheet transversely, the draft of the spring 35 falls inside said pivot pin or screw and hence acts to yieldingly hold the knife against the paper.

The operation is as follows: The shaft a³, is removed from the machine and inserted 40 through a roll of paper at the axis and inasmuch as such paper is ordinarily rolled on about a half inch rod, a three-eighths inch rod is preferably utilized for the shaft for said roll. Having secured the roll of paper 45 thereon and returned the flanges a⁴, to place, the roll is dropped into the yoke brackets affording its bearings, the paper is passed over the lower cutting roll b⁴, over the pasting roll, and beneath the front roll a². The 50 upper cutting roll b, having been returned to position or placed upon the paper where it passes over the roll b⁴, a slight pull on the paper around the roll a², serves to draw the roll inwardly rotating the pasting roller B, 55 and the cutting rolls and serving to simultaneously paste and trim the paper for the desired length. When the desired length of paper for the room height has been pasted and trimmed, the operator swings the arm E, inwardly so that the spring e⁶, draws the 60 upper ends of the yoke arms E, firmly inwardly with the straight edge e', bearing against the paper where it is drawn around the roll a². The operator now, by means of 65 the handle e⁵, swings the cutter away from

the paper and moves the cutter to one of the limits of movement between the yoke arms, then bracing the same firmly against the paper steel roll, moves the same for the entire width transversely the machine, thus 70 severing the paper by one movement, the straight edge, of course, serving to prevent wrinkling or tearing during the cutting operation, the operation being materially assisted by the rotary wheel which is employed instead of an ordinary knife. As the 75 paper is drawn through the machine the ends are folded back to fold the pasted surfaces inwardly, as usual. A sufficient number of strips having been prepared of the requisite 80 length, the operator then applies them to the wall in the usual manner.

Of course, heretofore the operator has of necessity handled his paper a number of times before ready for application, namely, 85 he first measures the paper and cuts off the desired length, then trims, then pastes, then folds, and then applies. As above described, however, the operator performs all these operations practically in one, obviating the 90 danger which always exists of soiling delicate papers by repeated handling heretofore necessary and owing to the numerous separate operations that are here combined in the operation of a single machine, he is 95 able to accomplish much more in a given day than has heretofore been possible.

Of course, I am aware that very numerous details of construction may be varied and I therefore do not purpose limiting this application otherwise than necessitated by the prior art.

I claim as my invention:

1. In a machine of the class described a receptacle, means rotatively supporting a roll of paper at one end of the same, rolls through which the paper is drawn, a pasting roll journaled beneath the paper, trimming cutters positioned at one side the machine to trim the paper longitudinally while pasting the surface, means for severing the paper transversely, means for holding the paper while the same is being severed and means for yieldingly forcing the holding means against the papers during the severing operation.

2. A receptacle for paste, a pasting roll journaled therein, means guiding the paper to be pasted over the pasting roll to spread the paste thereon by rotation, rotary cutters for trimming one or more edges of the paper, a straight edge pivotally supported on the end of the machine and adapted to bear on the paper transversely when swung inwardly, and a cutter operating adjacent the straight edge to sever the paper transversely.

3. In a machine of the class described a paste receptacle, rollers journaled thereon, one of which is adapted to receive a roll of

paper, cutting rolls for trimming the edge of the paper, a straight edge adapted to bear positively on the paper and a cutter pivotally supported to first be swung to contact the paper and then rotated to sever the paper transversely.

4. In a machine of the class described a receptacle for paste, a pasting roll rotative therein and projecting above the same, means feeding the paper thereover with the back surface contacting the same, a forward roll, an operatively connected straight edge and cutter, the former to bear on said forward roll adjacent the cutter and the latter to be drawn transversely the sheet in severing.

5. In a machine of the class described a receptacle for paste, a pasting roll rotative therein, and projecting above the same, means feeding the paper thereover, with the back surface contacting the same, a forward roll, an operatively connected straight edge and cutter, the former to bear on said roll adjacent the cutter, the latter to be drawn transversely the sheet in severing and an adjustable scraper for removing the excess paste from the pasting roll.

6. In a machine of the class described the combination with means for rotatively supporting the roll of paper, of tension or feed rolls journaled one upon the other in advance thereof, coacting cutters thereon for trimming the edge of the paper, a paste roll journaled in the receptacle and over which the back of the paper is drawn, a scraper to remove excess paste therefrom, a forward roll about which the paper is drawn, a spring supported, straight edge adapted to bear on said paper at said roll and a rotary

cutter movable longitudinally the roll and straight edge and acting to sever the strip on said forward roll.

7. In a device of the class described a paste receptacle, means at one end of the receptacle for supporting paper, means for trimming the paper longitudinally, means for applying paste to the paper, a roller around which the paper passes after the paste is applied thereto, a guide shaft adjustable to and from the roller, a rotary knife slidably carried by the guide shaft and means for manual engagement for sliding the knife transversely the paper to sever the paper.

8. In a device of the class described a paste receptacle, means for rotatively supporting a roll of paper, a plurality of rollers between which the paper passes, coacting rigid and adjustable cutters on said rollers, means for forcing the adjustable cutters inwardly to coact with the rigid cutters, means for pasting one side of the paper, a roller over which the paper passes after leaving the pasting means, pivotally supported means for pressing the paper against the last named roller prior to severing the paper, a rotatable cutter movable above the pressing means and a spring for holding the cutter yieldingly against the paper that is being severed.

In testimony whereof I have hereunto subscribed my name in the presence of two subscribing witnesses.

GEORGE C. BAUMAN.
